UNITED STATES PATENT OFFICE.

MORRISON J. BARNETT, OF SAN FRANCISCO, CALIFORNIA.

TIMER.

1,312,885.

Specification of Letters Patent.

Patented Aug. 12, 1919.

Application filed October 24, 1916. Serial No. 127,377.

To all whom it may concern:

Be it known that I, MORRISON J. BARNETT, a citizen of the United States, residing at San Francisco, in the county of San Francisco and State of California, have invented new and useful Improvements in Timers, of which the following is a specification.

The present invention relates to improvements in timing devices, such as are used for timing the exposures of photographic cameras, one object of the invention being to provide a device of this character which will be compact in form, and simple and inexpensive in construction. A further object is to provide a needle valve, which can be accurately adjusted so as to regulate the rate of flow of the fluid past the valve, which will afford an excellent indication of said rate of flow, which, when set, will not move from the position to which it has been adjusted, and which will be provided with means for limiting the extent of adjustment.

In the accompanying drawing, Figure 1 is an end view of my improved timing device in its position before the commencement of the operation of timing; Fig. 2 is a longitudinal section of the same in the same position; Fig. 3 is a view of the other end of said timing device in said position; Fig. 4 is an end view of the timing device in its position at the end of said operation of timing; Fig. 5 is a broken side view of the same; Fig. 6 is a view similar to Fig. 4 showing the timing device attached to a camera, the latter being shown as broken; Fig. 7 is a side view of the same; Fig. 8 is a broken side view of a cable release; Fig. 9 is a side view, on a small scale, showing the timing device attached to the camera in a manner different from that in Fig. 7.

Referring to the drawing, 1 indicates a cylinder, of which one end is pressed inwardly and back on itself to form a double wall 2, then a closed end 3, and then, around the center of said closed end, an outwardly extending cylindrical wall 4, threaded on its inner surface to receive the threaded portion 5 of a needle valve 6, said needle valve extending through a minute hole in the center of the closed end. Secured to the outer end of said threaded portion 5 is a double pointer 7 of spring metal, the ends of which are, by the screwing in of said needle valve, pressed against the rounded outer edge of the double wall, said double pointer thus acting as a friction device to lock said valve, holding it

firmly in any position to which it may have been adjusted. Soldered or otherwise secured to the inner side of said double wall is a pin 8, forming a stop for the double pointer 7, the parts being so arranged that, when one end of the pointer is stopped by said pin, as shown in Fig. 3, the minute hole is completely closed by the needle valve. On the inner surface of the double wall is marked a circular series of equally spaced lines 9 indicating to what extent the valve has been opened.

The other end of the cylinder is closed by a head 11, held in place by the metal at said end of the cylinder being swaged around the edge of said head. Said head is formed with a central non-circular aperture 12, in the present instance shown as a square aperture, best shown in Fig. 1. Through said aperture extends a stem 13, the inner end of which is threaded, as shown at 14, said threaded end passing through a plunger 15 consisting of first, a metal disk 16, then a leather cup 17, then a metal disk 18, there being finally screwed upon said threaded end the inner end of a nut 19, the outer end of said nut forming a stop abutting against the closed end around the needle valve and preventing the needle valve coming in contact with the inner end of the stem 13. Around the inner portion of the stem is coiled a spring 20 compressed between the plunger 15 and the head 11 of the cylinder, when the stem is drawn outward as far as possible. The outer end of the stem is in cross section of form corresponding to that of the aperture 12, that is, in the present instance, square, so that, when turned in any one of four positions, the stem can slide through the aperture 12, but when turned out of those positions, the inner end of the outer portion forms a shoulder, resting against the head 11 of the cylinder and preventing the inward movement of the stem and plunger. The extreme outer terminal portion of the stem is bent at right angles, as shown at 21, thus forming a convenient handle for drawing out the stem against the pressure of the spring. Adjacent to the plunger when in its outermost position there is formed through the wall of the cylinder, a small hole 22, through which air can enter the cylinder when said stem has been drawn outwardly to its full extent.

Soldered or otherwise secured to the cylinder near the end closed by the head 11, and

extending outwardly from said cylinder is a clip or holder 23 comprising two yokes 24 of spring metal, the free edges of which yokes converge toward each other. In these yokes 5 can be inserted a head 25 of a casing 26 of a release rod 27 which is connected to a cable 28 of a camera shutter. The handle 21 when turned from the position shown in Fig. 1 to the position shown in Fig. 4, can form 10 a pressure arm to engage the head 29 of the rod 27, and, when the spring 20 is allowed to expand, the head 29 of the release rod 27 will be moved in the proper direction to operate the release rod 27 to make an exposure 15 of the camera, to the shutter of which the cable 28 is attached.

In the form of the invention shown in Figs. 6 and 7, the cylinder 1 is attached to a camera 30 by a spring clip 31, and the handle 21 engages a lever 32 of well known construction to cause an exposure of the camera.

In Fig. 9 the cylinder is shown as attached to the shutter of the camera by a band 33, and the handle 21 engages a well known form of lever 34 for operating the camera shutter.

I claim:—

1. In combination with a needle valve, a partition having an aperture adapted to be closed by said valve, a threaded casing in 30 which said needle valve is screwed, and a straight wall remote from said casing, and a straight double-ended pointer attached to said needle valve and having both of its ends movably 35 and frictionally engaging said wall.

2. In a timing device, the combination of a cylinder having a vent aperture, a plunger therein, a stem therefor, said cylinder having a hole through which said stem 40 passes, the outer portion of the stem being cross-sectionally of a form such that it can

pass through said hole when in one position, but cannot pass therethrough when turned about its axis from said position, and a spring pressing said stem against said plunger. 45

3. In a timing device, the combination of a cylinder having a vent aperture, a plunger therein, a stem therefor, said cylinder having a hole through which said stem passes, the outer portion of the stem being cross-sectionally of a form such that it can pass through said hole when in one position, but cannot pass therethrough when turned about its axis from said position, and a spring 55 pressing said stem against said plunger, the outer terminal portion being bent to form a handle and pressure arm.

4. In a timing device, the combination of a cylinder having a vent aperture, a plunger therein, a stem therefor, said cylinder having a hole through which said stem passes, and a spring pressing said stem against said plunger, the outer terminal portion carrying a pressure arm and the cylinder being provided with a stationary holder 60 for holding the casing of a cable release rod adapted to be actuated by said pressure arm.

5. In a timing device, the combination of a cylinder having a vent aperture, a plunger 70 therein, a stem therefor, said cylinder having a hole through which said stem passes, and a spring pressing said stem against said plunger, the outer terminal portion carrying a pressure arm and the cylinder being provided with a spring clip 75 consisting of two spring yokes having converging free edges for holding the casing of a cable release rod adapted to be actuated by said pressure arm.

MORRISSON J. BARNETT.
